Primary Examiner — Ania Aman(74) *Attorney, Agent, or Firm* — Dunlap Bennett & Ludwig, PLLC(57) **CLAIM**

I claim, the ornamental design for a front cowl for a vehicle, as shown and described.

DESCRIPTION

FIG. 1 is a top front right perspective view of a front cowl for a vehicle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a right side elevation view thereof, shown in use with a vehicle.

The broken lines shown in FIGS. 2-5 and 7 depict portions of the front cowl that form no part of the claimed design. The broken lines shown in FIG. 8 depict environment of a vehicle that forms no part of the claimed design.
